UNITED STATES PATENT OFFICE.

HANS HONIGMAN, OF DULUTH, MINNESOTA.

AMUSEMENT DEVICE.

1,326,592.

Specification of Letters Patent. Patented Dec. 30, 1919.

Application filed February 24, 1919. Serial No. 278,890.

To all whom it may concern:

Be it known that I, HANS HONIGMAN, a citizen of the United States, residing at Duluth, in the county of St. Louis and State 5 of Minnesota, have invented certain new and useful Improvements in Amusement Devices, of which the following is a specification, reference being had therein to the accompanying drawing.

10 This invention relates to amusement devices and refers particularly to what may be termed a child's coaster.

The principal object is to produce a device of this character which is attractive 15 and one that will afford healthful and safe amusement to children.

Another object is to produce such a device simple of construction and one that may be conveniently stored away when not in use.

20 Other objects and advantages of the novel construction will appear as the description thereof proceeds.

In the accompanying drawings, forming part of this application, and in which like 25 reference characters indicate like parts,

Figure 1 is a side elevation of the coasting device, with the vehicle in receptive position for an occupant;

Fig. 2 is a transverse sectional view taken 30 on the line 2—2, Fig. 1, looking toward the upper end of the device;

Fig. 3 is a top plan view of the upper end of Fig. 1, and

Fig. 4 is an elevation of the spring-actuated mechanism viewed from the opposite side to that shown in Fig. 1.

The embodiment of the invention herein illustrated comprises two inclined members 1—1, being held together by the board 2 rigidly fixed to the upper edges thereof. 40 The lower ends of the members 1 are beveled, as at 3, to rest snugly upon the surface when the opposite end is elevated upon the legs 4—4. The legs 4—4 are united by 45 suitable cross-pieces 5 and 6, forming a head-frame, which is pivotally attached to the outside of the members 1—1 by suitable screws or bolts 7.

Intermediate of the members 1—1 and 50 adjacent the pivotal connections of the head-frame, is pivotally mounted, as at 8, a cross-piece 9. Upon this cross-piece 9 is securely fixed the board 10, which thus becomes rockable upon said pivots 8—8. This board 55 10 forms a platform for the reception of the four-wheeled vehicle 11, and when in

its normal level position, or, if preferred, slightly tipped backward, rests upon the beveled upper ends of the members 1—1, as at 12.

60 The under edges of the members 1—1 rest upon the cross-piece 6 when the headframe is in its upright supporting position and thus prevent the structure from collapsing in one direction and in the opposite direction is held intact by the spring-controlled dog 13, pivotally mounted at 14 to the inner side of one of the members 1, the free end 15 of which engages the innermost side of the cross-piece 6, thus preventing jack-knifing 65 of the structure.

The contractile spiral spring 16 is attached 70 to the dog 13 adjacent its pivotal connection 14, as at 17, and the opposite end attached to the under edge of the cross-piece 75 9, as at 18. In this manner the cross-piece 9 is normally tilted with the board 10 resting upon the inclined ends of the members 1—1, and in a horizontal position, while the same stress of the spring normally holds the 80 dog 13 contacting the cross-piece 6, as shown.

When the free end 15 of the dog 13 is manually depressed so as to allow the head-frame to be brought up upon its pivotal 85 supports 7, it is evident that the structure will occupy much less space thus folded and may be conveniently stored or shipped in such position.

The vehicle 11 is of light, simple and 90 cheap construction and may be placed upon the platform 10 and mounted when in its horizontal position. Then when the rider is ready to slide, a slight leaning forward motion will tip the platform forwardly until 95 in the same plane with the board 2, when the vehicle will readily run by gravity down the inclined plane thus formed, and a pleasurable experience to the occupant results.

100 Channels, or grooves, 19 are formed longitudinally the board 2 and adjacent the edges thereof and similar channels 20 are formed in the platform 10, to act as guides for the wheels of the vehicle.

105 Three sides of the platform 10 are surrounded by an upstanding molding 21, to assist in the convenient applying of the vehicle to the platform and to insure its starting properly on its journey, within the 110 channels.

To the lower forward end of the board 10

and centrally thereof, is attached a piece of resilient material, such as leather, or the like, and which extends upwardly over the end of the board. This is for the purpose 5 of wedging slightly intermediate of the ends of the boards 10 and 2, when the former is fully tipped downwardly to register with the latter and by this means the board 10 is temporarily held in such position. This is to prevent the board 10 from 10 snapping upwardly too suddenly after the passage of the vehicle thereover and is found to be convenient in the operation of the device. This resilient material is indicated 15 at 22.

Having thus described my invention, what I claim as new, and desire to secure by Letters Patent, is:

1. An amusement device comprising an 20 inclined track, an upright pivoted support at the upper end of the track supporting same in its inclined position, a vehicle made to coöperate with the track, a pivoted vehicle-receiving platform at the upper end of 25 the track adjacent the support and means normally holding the platform in horizontal position and the support in upright position.

2. An amusement device comprising an inclined track, a pivoted support for the 30 upper end of the track, a vehicle made to coöperate with the track, a pivoted vehicle-receiving platform at the upper end of the track adjacent the support and a spring-actuated pivoted dog adjacent the pivotal

connections of the platform and support 35 normally holding same in their operative positions.

3. The combination with a sectional inclined runway of the character described and a coasting vehicle therefor, one section 40 of the runway being stationary and the other section being pivotally mounted and intermittently coöperative with the other section, of automatically operated frictional interlocking means intermediate of the two 45 sections for temporarily holding the sections in coöperative alinement and means for normally holding the sections out of alinement for the purpose described.

4. The combination with an inclined runway of the character described, an adjustable vehicle-receiving starting platform at the upper end thereof and a wheeled vehicle therefor, of an upright support at the upper end of the runway and pivotally attached thereto and means coöperatively engaging with the runway and support starting platform for normally holding them in position for the reception of the car prior to its starting down the runway. 50

In testimony whereof I have hereunto affixed my signature in the presence of two witnesses.

HANS HONIGMAN.
